[57] CLAIM

The ornamental design for an infant car seat having retractable legs, as shown and described.

DESCRIPTION

FIG. 1 is a front, top and side perspective view of the infant car seat having retractable legs showing our new design;

FIG. 2 is a front elevational view thereof;

FIG. 3 is a rear elevational view thereof;

FIG. 4 is a side elevational view thereof, the side opposite being a mirror image of the side shown in FIG. 4;

FIG. 5 is a top plan view thereof;

FIG. 6 is a bottom plan view thereof; and,

FIG. 7 is a perspective view thereof with the legs retracted.

FIG.1.

FIG. 2.

FIG. 4.

FIG. 3.

FIG. 5

FIG. 6

FIG. 7.
